UNITED STATES PATENT OFFICE.

ERSKINE RAMSAY, OF BIRMINGHAM, ALABAMA.

SYNCHRONIZED ROTARY DUMP.

Application filed December 15, 1923. Serial No. 680,935.

To all whom it may concern:

Be it known that I, ERSKINE RAMSAY, a citizen of the United States of America, residing at Birmingham, in the county of 5 Jefferson and State of Alabama, have invented certain new and useful Improvements in Synchronized Rotary Dumps, of which the following is a specification.

My invention relates to an improvement 10 in dumps which is characterized by the fact that the dump's movements are synchronized or co-ordinated with the drive for mechanism that handles or treats the dumped material, such as a feeder and screen, so that 15 the dumping mechanism can take charge of a train of coupled or uncoupled cars and automatically dump them singly or in groups of two or more at proper time intervals so that the material dumped is not 20 delivered to the feeding and screening mechanism at a rate faster than they can properly handle it. The entire dumping, feeding and, if desired, screening mechanism, being automatically controlled and 25 synchronized, enables the operation of the entire mechanism to be timed so as to produce the best operating results throughout.

My invention also comprises the provision of novel and effective means for controlling the automatic operation of the dump by a latch means releasable responsive to the joint action of a loaded car in or approaching the dump, either or both, and a trip operated by the synchronizing mechanism which is co-ordinated with the drive 30 for the feeder or screen.

My invention also comprises the provision of a supplemental latch manually controllable and normally held inoperative by means 40 of which the dumping can be stopped at any time.

My invention further contemplates the provision of a scale associated with the dump in accordance with Letters Patent No. 45 852,643, issued to T. H. Aldrich, Jr., and assigned to me, there being provided, subject to the control of the dump, two sets of stop dogs in the approach track, one adapted to arrest a car on the scale and the 50 other to arrest a car in position to pass onto the scale after the next operation of the dump. By this arrangement my automatic control of the dumping takes care of the weighing also of the loaded cars, the weight

being either mechanically recorded or entered by the scale or dump control man. 55

My invention also comprises novel means automatically controllable by the dump for releasing the car stops which control the movement of cars to and through the dump. 60

My invention contemplates the delivery of the cars as fast as they are received from the mine to a track preferably inclined so as to feed them by gravity to the dump, and when the mechanism has automatically dumped all but the last two loaded cars it will stop ready to resume dumping when any additional cars reach the track trip plate, thus leaving the mechanism always ready for automatic operation without requiring any resetting of the automatic mechanism. 65

My invention further comprises the novel details of construction and arrangements of parts, which in their preferred embodiments only are illustrated in the accompanying drawings forming a part of this specification, and in which:— 70

Fig. 1 is an end elevation of a rotary dump showing the feeder and screen with which its dumping movements are synchronized. 75

Fig. 2 is a plan view, and Fig. 3 a side elevation of the dump and track mechanism, omitting the synchronizing mechanism and most of the tipple structure. 80

Fig. 4 is a diagrammatic view showing the dump control latches separated to better illustrate the individual control for operating each latch. 85

Fig. 5 is an end view of the assembled latches; and 90

Fig. 6 is a side view of the latches showing a part of the dump. 95

Fig. 7 is a view of the track stop dogs and their operating shafts. 100

Fig. 8 is a similar view of the dump stop dogs and their operating mechanism.

Fig. 9 is a detail view of a modified form of stop. 105

Fig. 10 is an enlarged view in plan broken away to show the operating mechanism for the stop dogs on both the dump and approach track.

Fig. 11 is a diagrammatic layout of the synchronizing drive for twin dumps and the feeder and screen mechanism for handling them. 110

Fig. 12 is a detail view illustrating the manner of operation by a trip on the dump of the rocker shaft which opens the track dogs.

5 Similar reference numerals refer to similar parts throughout the drawings.

According to the embodiment of my invention illustrated in the accompanying drawings, I show in Fig. 1 a tipple structure comprising uprights 1 and lower cross beams 2 and upper cross beams 3, all of any suitable material and assembled in accordance with any present practice. The beams 2 support suitable bearings, not shown, for the trunnion rollers 4 upon which the riding rings 5 of the dump rest and by which they are supported free for rotation about the long axis of the dump. The dump is of any suitable structure, that shown comprising the riding rings 5 formed of bent rails having their inturned bases cross connected by longitudinal plates 6 on each side and 7 at the bottom, the plate 7 carrying upwardly divergent braces 8 which are riveted to the brackets 9 which support the hold-down bars 10 that overhang the car axles 11, or if desired the wheels 16. The brackets 9 also support the cross bars 12 upon which the track rail sections 13 are mounted in the dump. The dump is also preferably counterweighted by one or more elements 14 which as shown are in the form of hollow members or pipes adapted to receive any suitable weight with which to unbalance the dumping structure in the direction of its rotation to dump. The dumping structure as thus far defined is that considered preferable for the purposes of my invention, but obviously it may be widely varied as to type and design according to conditions of use or to methods of operation required at each installation.

The cars 15 which are to be dumped are conventionally illustrated and are mounted on wheels 16 on the axles 11. My invention, though capable of dumping more than one car at a time, is shown adapted to dump a single car and the dumping structure being short is provided with only a single stop lug 17 attached to one of the dump rings 5 in position to be engaged by a series of latches 18, 19, 20 and 21, all mounted on a common shaft 22 in bearings 23 on uprights 24 of the tipple superstructure. These latches all have similar detents set in the same plane and all adapted to engage the same lug 17 and hold the dump against movement in the direction of the arrow (Fig. 1), which is its direction of rotation as it moves to dump.

The latch 18 has an arm 25 projecting below its pivotal bearing and connected by a cross rod 26 to a crank 27 fast on a shaft 28 extending longitudinally past the dump and up along the approach tracks 29 to

the point where it is desired to place the track trip plate 30. As shown in Fig. 2, this shaft 28 extends past the scale tracks 31, passing freely therethrough so as not to interfere with the weighing operation 70 and to a point so spaced from the scale track that a car brought to rest by the dogs 32 on the plate 30 will stand about the same distance from a car brought to rest by the dogs 33 on the scale as the said 75 latter car is from a car brought to rest by the dogs 34 within the dump. The exact spacing of the cars is not essential but it is desirable that they should be substantially equi-distant so that they will all move 80 within approximately the same time whether coupled or uncoupled from each position to the next succeeding position in the dumping operation. The car trip 30 is in the form of a plate fast on the shaft 28 and 85 adapted to be depressed by the flanges of the wheels of a loaded car and when so depressed it acts to release the trip 18 from engagement with the dump lug 17. The latch 19 is connected by a rod 35 to a rocker arm 36 pivotally mounted on a bearing bracket 37 attached to the superstructure and adapted at its upper end to be engaged and operated by a cam 38 fast on a rotatable disk 39 driven by the synchronizing 90 mechanism which will be later described. The latch 20 is connected by a rod 40 with the lower end of the bar 41, also pivoted to the bracket or support 37, and at its upper end connected to a chain or pull cord 42 leading to any suitable point on the tipple from whence it can be manually controlled. The latch 21 is provided with a depending arm 43 having a laterally out-turned end which carries a right angled latch bar 44 adapted to be engaged and pulled by a bar 45 having a shoulder 46 which engages over the out-turned end of the latch bar 44. The bar 45 is pivotally connected to a crank 47 fast on a rocker shaft 48 journaled in 100 the dump and carrying fast thereon a dump trip plate 49 which is normally held in raised or operating position by a coil spring 50. When a car is in the dump, wheel flanges thereof depress the trip 49 and through the connections described disengage the latch 21 from the dump lug 17. I provide springs 18^a, 19^a, 20^a and 21^a for the latches 18, 19, 20 and 21, respectively, 105 adapted to press the latches towards lug engaging or operating position. The chain 42 is attached to some suitable anchor and adapted to pull the latch 20 out of lug engaging or operation position. From this 110 it follows that when the hand controlled latch 20 is not released to assume operating position it stands in inoperative position and the latches 18, 19 and 21 alone 115 control the release of the dump to operate. The several springs are mounted on 120

a common support 42^a on the tipple superstructure.

From the foregoing description it follows that when a loaded car assumes position against the dogs 34 in the dump the latch 21 is disengaged and when a loaded car on the approach track assumes position against the dogs 32 to depress the track trip 30 the latch 18 is disengaged. The dump 10 unbalanced is then free to rotate except for the latch 19 and as soon as this is disengaged by the action of the synchronizing mechanism the dump is free to rotate. The dump 15 is adapted to swing part way over, being unbalanced to one side by the weights and, if desired, by the car being off center as shown and having its center of gravity above the dump center. After the load is emptied from the car its dump becomes un- 20 balanced by the weights to swing back and its center of gravity again comes above its axis of rotation and thus the dump will swing back in a reverse direction to its initial position. The dump can be brought 25 to rest in this position by any suitable stop 51 and its lug will engage the bevelled faces of the latches and move past them sufficiently for the latches to snap into operating position above it. A similar stop 51^a may be 30 mounted on the superstructure in position to stop the dump after it dumps, and both stops may carry spring means to absorb the stopping shock and accelerate the starting movement therefrom.

35 The synchronizing mechanism controlling the cam disk 39 will be best understood by reference to Figs. 1 and 11. The cam disk is fast on a shaft 52 mounted in suitable bearings on the superstructure and carrying 40 a sprocket wheel 53 driven by a chain 54 from a sprocket 55 on a countershaft 56. Where only a single dump is employed this countershaft will carry only one sprocket 55, but where the mechanism is adapted to 45 control a pair of dumps, as shown in Fig. 11, a second sprocket 55 will also be mounted on the shaft 56 and will, through a chain 57 and sprocket 58, drive a cam disk shaft 52^a, corresponding to 52, carrying a disk 39^a corresponding to 39 and controlling the 50 second dump. The countershaft 56 has a sprocket 59 thereon driven by a sprocket chain 60 from a sprocket 61 on the shaft 62, which is driven by a belt 63 and variable 55 speed pulleys 64 and 65 from a shaft 66 which derives its power from a belt 67 driving a pulley 68 on the shaft 66. A pulley 69 on the shaft 62 is adapted by means of a twisted belt 70 to drive a pulley 71 on a 60 feeder drive shaft 72. The shaft 72 carries a sprocket 75 on the screen drive shaft 76. These shafts 72 and 76 are suitably mounted, the bearings not being shown, and shaft 72 has fast thereon eccentrics 77 which by 65 means of eccentric rods 78 will give a bal-

anced drive to the reciprocating plate feeder 79. This feeder receives the material from a hopper 80, into which it is discharged from the dump, and the feeder plates as they are reciprocated will move the feed openings 70 therein back and forth under the hopper and serve to feed the material to a reciprocating screen 81 also driven by eccentric rods 82 from eccentrics 83 on the shaft 76. The feeder and screening mechanism are preferably constructed and driven as described in my pending application, Serial No. 586,378, filed Sept. 5th, 1922.

From the foregoing it follows that both the reciprocating feeder and screen are 80 driven from the same mechanism which rotates the cam disk 39 and that this cam disk will act periodically to release its latch 19 once for any desired predetermined number of reciprocations for the feeder and screen. 85 Theoretically the cam disks are moved slowly so that it will require a greater time interval for them to complete a revolution than is required for the dump to operate and return to initial position and for the 90 empty car to pass off the dump and a loaded car to assume position on the dump. Hence, must the car await the trip of the cam controlled latch 19 before it can operate and by this means it is synchronized with the 95 operation of the feeder and screen so that all of the agencies of the dump are co-ordinated and are capable of acting with highest efficiency, one not overloading the other.

I have already referred to three sets of 100 stop dogs 32, 33 and 34. These dogs may be of any suitable construction, that shown comprising a vertical notched stop plate having a hub portion 84 mounted to rock on suitable journals or axes on the approach track and in the dump, as the case may be, each dog having an offset depending crank arm 85 with holes 86 and 87 therein. These dogs are arranged in opposite pairs on the outer side of the track rails and are normally pressed into operating or car stopping position, as shown in Fig. 10, by the action 105 of a compression spring 88 which surrounds a rod 89 that has an angled end mounted in the hole 86 of one dog of a pair and has its other end telescoped into a pipe 90 which carries an angled rod 91 that engages in the hole 86 in the opposite dog. Each compression spring bears against a seat 92 fast on 110 its rod 89 and against a washer 93 at the inner end of its pipe 90 and thus normally and yieldingly presses its respective dogs into car stopping position in which they overhang the track. The dogs are adapted 115 to be opened up by chains 94 connected to the lower hole 87 in each dog arm and at their other ends connected to the opposite ends of a bar 95 which at its center is clamped to a rocker shaft. The bars 95 controlling the dogs 32 and 33 are fast on the 120 125 130

rocker shaft 96 which extends along the approach track and has fast on its end adjacent to the receiving end of the dump a crank member 97, preferably in the form of a casting recessed to receive in its free end a coil spring 98 which presses against a seat fast on a stop pin 100 and tends to press this pin into position to be engaged by a trip plate 101 mounted fast on the receiving end 10 of the dump. The pin is connected by an operating rod or bar 102, having an adjustable turn buckle 103 therein, to one end of a bell crank lever 104 pivoted in the approach track between the dogs 32 and 33 and disposed with its free end adjacent to one of the track rails and adapted to be moved by a car, just after it has passed the dogs 32, and caused to pull out the latch pin 100 against the action of its spring. Before the 20 car that last operated the trip 104 has reached the dogs 33, the pin 100 has been released, freeing the crank member 97 from the trip plate 101 and releasing the springs 88 to reset the dogs 32 and 33. As soon as 25 the dump moves from initial position to dump the spring 98 projects the latch pin into the path of the dump trip plate 101. The pin stands in engagement with the outer face of this plate 101 after being retracted 30 by crank 104 until the dump starts its dumping rotation. When the plate 101 moves from in front of the pin 100 the latter is free to project still further towards the dump so that as the dump swings back to 35 initial position the trip plate 101 will strike the pin and rock the crank element 97 from dotted to full line position, Fig. 12. This rocks the shaft 96, as shown in Fig. 7, and pulls the chains 94 so as to open out the dogs 40 against the tension of the springs 88. The dogs will remain in open position for the loaded car to pass until the crank 104 is actuated, pulling the pin 100 inwardly out of engagement with the edge of the stop 45 plate 101 and allowing the springs 88 to snap the dogs 32 and 33 inwardly and reset the crank element 97 in approximately upright position, as shown in Fig. 10, the pin remaining still in engagement with the end 50 face of the trip plate 101 until the dump next moves to dump, whereupon this plate moves past the pin and the latter snaps again into its path as it returns so that the crank element 97 will be again rocked over 55 and the dogs again opened after the next dumping operation.

With reference to the dogs 34 in the dump, these are operated by chains 94 connected to a bar 95 fast on a rocker shaft 105, which 60 element extends approximately to the discharge end of the dump and there has fast on it a segmental crank plate 106 which is adapted to engage a spring-pressed trip pin 107 reciprocable axially in spaced bearings 65 108 mounted fast in the receiving track be-

yond the dump. A coil spring 109 surrounds the pin between the bearings and presses it towards the dump into its operating position. The spring at its end towards the dump engages a forked plate 110 which is fast on a rocker shaft 111 carrying a crank 112 having a trip arm 113 adapted to be engaged and rocked by the wheels of an empty car as it passes off the dump and onto the "empty" track. This empty car 75 thus retracts the pin 107 from position in front of the plate 106 and releases this plate, responsive to the tension of the dump spring 88, to move as shown in Fig. 8, and permit the dogs 34 to move inwardly to closed position. In thus rocking the segmental plate does not move entirely past the pin but holds it until a movement of the dump will swing it past the pin, thereby releasing the latter to snap into full operating position in 80 the path of the returning plate 106. It thus follows that the movement of the dump as it swings back to initial position after a dumping operation will act to open all of the dogs and all will be held open until the 85 movement of cars past the dogs 32 and 34 has tripped the pins 100 and 107, and when this occurs the dogs snap back into car stopping position and remain in that position until the completion of the next dumping 90 operation.

In operation, referring to Fig. 2, and assuming loaded car A in the dump, loaded car B on the scale, and loaded car C in engagement with the track dogs 32, the dump 100 is ready to commence automatic action, provided the hand controlled latch 20 is open. Normally this is held open and the dumping operation proceeds as follows. The dump when released by the synchronizing mechanism swings automatically by gravity to dump car A and as it swings back the trip plate 101 thereon moves the track rocker shaft 96, and the shaft 105 on the dump is rocked by track pin 107 engaging the member 106. Both shafts are thus rocked, as shown in Figs. 7 and 8, and all stop dogs will be opened. Thereupon the dumper car A is released to roll out of the dump, the loaded car B is released to roll into the dump, loaded car C is released to roll into 110 position on the scale and the next loaded car approaches the dogs 32 which have been released to reset as soon as car C had tripped the latch 104 and the empty car A had 115 tripped the latch 107. The loaded car B and the loaded car following car C will be stopped by the dogs, and when the latter car assumes position on trip plates 30 and 49 it will move them to release all of the latches except the synchronizing latch 19 and this releases the dump to operate after the predetermined time interval has elapsed, its controlling cam 38 tripping the latch 19, whereupon the dump commences a new op- 120 125 130

eration, and the same cycle repeats itself as long as there are cars to depress the trip plate 30. At all times the dump is only released for operation at the timed intervals controlled by the cam 38. When there are no longer cars to depress the trip plate 30 the automatic dumping operation ceases and the remaining cars in the dump and scale can only be dumped if desired by the manual release of the latch 18. By holding the hand latch 20 in operating position and by pressing the dogs 32 and 33 out of car stopping position, loaded cars can be again brought into position in front of each pair of dogs 33 and 34 and the automatic operation can be resumed. Normally two loaded cars will be left, one in the dump and one on the scale, and the whole apparatus will resume automatic dumping as soon as any additional cars are fed to the approach track and reach the trip plate 30, after which the operation will continue as long as there is a car to depress the trip plate 30.

If it be desired to pull the empty cars back through the dump, I use the type of dog shown in Fig. 9, where the stop plate 114 is elongated and provided with an out-turned end 115 towards the dump, which end will be engaged by the car wheels so that the latter can wedge the dogs apart and pass them. I have shown the track scales, but if other means of weighing the cars is desired, such may be used and the track scale and its dogs 33 can then be omitted.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a dumping apparatus, in combination, a dump, agencies automatically controlled by the dump to feed loaded cars to and empty cars from the dump, a hopper to receive the material dumped, a feeder to discharge the material from the hopper, latch mechanism operable to release the dump for its dumping movement, and a drive for the feeder and which trips said latch mechanism to co-ordinate the operation of the dump and feeder.

2. A dumping mechanism in accordance with claim 1, in combination with a screening mechanism which receives the material from the feeder and is operated by said common coordinating drive.

3. In combination, a rotary dump, dump controlled means for the automatic delivery of cars to and discharge from said dump, a latch to control said dumping operations,

mechanism to feed and screen the material discharged, and a common co-ordinated drive for operating said feeding and screening mechanisms and effecting the periodic release of said dump latch, substantially as described.

4. In a dumping mechanism, a gravity operated dump, means controlled by the dump to deliver cars to and discharge them from said dump, a compound latch mechanism to control the release of the dump to operate, said mechanism comprising a latch releasable responsive to a loaded car reaching a predetermined position in the dump, and a latch intermittently released by mechanism independent of the dump, substantially as described.

5. In a dumping mechanism, a gravity operated dump, means controlled by the dump to deliver cars to and discharge them from said dump, a compound latch mechanism to control the release of the dump to operate, said mechanism comprising a latch releasable responsive to a loaded car reaching a predetermined position in the dump, and a latch responsive to an intermittently acting continuously driven trip element, substantially as described.

6. A dumping mechanism in accordance with claim 4, in combination with a variable speed drive for said intermittent latch release mechanism.

7. The combination with a dump and automatic agencies, responsive to the car and dump movements, adapted to control the feed of cars to the dump, the spotting of cars in the dump and the operation of the dump, of a periodic actuator adapted to control the complete release of the dump to respond to its automatic control agencies.

8. A dump in accordance with claim 7, in combination with means responsive to an empty car's movement for controlling the automatic discharge of cars from the dump.

9. The combination with a dump and a fixed approach track, of stop means in the dump and track for cars, of automatic agencies responsive to dump and car movements, adapted to control the feed of cars to and from the dump and the automatic operation of the dump, and a timed intermittently acting control means adapted to intercept the automatic operation of the dump until after predetermined time intervals.

10. In a dumping mechanism, a dump adapted to rotate, means controlled by the dump's movements to deliver cars to and discharge them from the dump, and a mechanism to control the release of the dump for automatic operation; said mechanism comprising means, responsive to the joint action of a loaded car after reaching a predetermined position in the dump and of an intermittently operated mechanism inde-

pendent of the dump, to control the dump's movements.

11. In a dumping mechanism, a dump adapted to rotate, means responsive to the dump's movements to deliver cars to and discharge them from the dump, and mechanism to control the release of the dump for intermittent automatic operation which is responsive to the joint control of an independent timing mechanism and of a loaded car after it has reached a predetermined position in the dump.

12. In a dumping mechanism, a rotary dump unbalanced to oscillate back and forth by gravity in dumping a car thereon, a plurality of latches to hold the dump in car receiving position, an approach track, car stopping dogs in the approach track and in the dump, means automatically controlling the release and reset of said dogs by the movement of the dump and of the cars released by the dogs, said latches comprising one releaseable responsive to a car assuming correct position on the dump, and a second latch releasable responsive to a car assuming predetermined position on the approach track.

13. A dumping mechanism in accordance with claim 12, in which a third latch is provided which is normally disengaged and having hand means to apply it so as to hold the dump when the other latches are released.

14. A dumping mechanism comprising a rotary dump having spring-pressed dogs

therein and a reciprocable element controlling them, an approach track having spaced pairs of spring-pressed dogs, and a reciprocable element controlling said dogs, a track scale set in advance of the dogs adjacent to the dump, means responsive to the movement of the dump as it returns to initial position after dumping to release all the dogs, a trip releasable by a car after passing the remote track dogs to reset both track dogs, a trip mechanism operable by a car passing off the dump to reset the dump dogs, and latch mechanism responsive to cars approaching the remote track and the dump track dogs, which latch mechanism controls the release of the dump to operate.

15. The combination with a dump and automatic agencies, responsive to car and dump movements, adapted to control the feed of cars to the dump and the operation of the dump, of a periodic actuator which controls the complete release of the dump to operate, and mechanism for handling the dumped material having a drive which controls said periodic actuator.

16. The combination of an automatic gravity operated rotary dump, mechanism for treating the dumped material, drive means for said mechanism, and means controlling the release of said dump to operate which are jointly responsive to car position and to said drive means.

In testimony whereof I affix my signature.

ERSKINE RAMSAY.
